UNITED STATES PATENT OFFICE.

PHILIP MUELLER, OF DECATUR, ILLINOIS, ASSIGNOR TO ADOLPH MUELLER, TRUSTEE,
OF DECATUR, ILLINOIS.

PORCELAIN OR ENAMEL-IRON SOAP CUP.

Application filed October 17, 1924. Serial No. 744,172.

The present invention relates to lavatory fixtures and supporting means therefor, and has for its object to provide means for securing a fixture to a flat wall, or other support in any desired location, in such manner as to give a snug, sanitary fit against the wall, and hold it firmly and secure it against movement, except when it is desired to unseat it for purposes of repair, replacement, or the like.

As an example of a fixture of this kind, a soap cup is shown and described, but the invention may be applied to other fixtures.

More particularly, the invention is designed for use with porcelain soap cups, so that a cup of this character may be mounted in a lavatory, either upon a finished wall, or upon a finished lavatory slab or member, with the securing parts so disposed that they will be entirely concealed, and sealed and protected from contaminating and unsanitary drip, with no unsightly or exposed fastening members. Furthermore, the arrangement is such that while the cup will be securely mounted, it can be readily removed when the necessity arises.

In the drawings herewith, I have shown an embodiment of my invention, but it will be understood that this illustration is in no sense restrictive, as variations in structure and design may be made and still be within the range of my invention.

In the drawings:—

Fig. 1 is a view in vertical section of a support with my novel soap dish and securing means mounted thereon.

Fig. 2 is a view in plan with part of the structure in section of the development shown in Fig. 1.

Fig. 3 is a view in rear elevation of my improved soap dish.

Fig. 4 is a view in elevation of one of the securing members of the fixture.

Fig. 5 is a view in vertical section of the member shown in Fig. 4.

Figs. 6 and 7 are an elevation and a vertical section respectively, of the other securing member of the fixture.

Referring to the drawings by numbers, like numbers indicating like parts in the several views, 10 denotes a support or wall upon which the cup is to be secured. The construction of this wall may vary, but in the present instance, it is shown as provided with a finished surface 11 which may be tiling, or other suitable finish. The soap cup 12 is here shown

as formed of porcelain, although obviously other materials may be used. It comprises the cup proper, and a back member 13. The cup proper is of not unusual shape, and has the ribs 14 to support the cake of soap, the drip openings 15 alternating with the ribs so as to give proper drainage, and the central opening 15 will preferably be enlarged to give a finger hole to lift the soap, if it should adhere to the cup, or be difficult to grasp from above.

The back 13 of the cup has a shallow recess, as shown at 16, so as to leave a flat marginal edge 17 extending around the entire back, with the exception of the point where this marginal edge 17 is broken by a recess 18, presently to be described. This marginal edge, it will be clear from Figs. 1 and 2, seats smoothly and snugly against the wall or support, so as to give a close finished joint between the support and the cup, giving a slightly appearance, and, furthermore, preventing drip or seepage behind the cup, all of which is desirable from a sanitary standpoint.

The back 13, which is of considerable thickness, as shown, has formed therein, in addition to the shallow recess 16, the relatively deep recess 18 heretofore referred to, this recess 18 having undercut and outwardly converging top and side walls, and is open at the bottom. The said recess 18 is designed to receive one member 19 of the securing means, this member 19 consisting of a metal hanger plate having depending legs 20, and provided with the marginal flange 21. The member 19 has the inclined wall 22, so as to give a wedge-like formation in vertical section, as shown in Figure 5. This results, when the member 19 is in place, in the recess 18, in providing a substantially wedge-shaped space between the inclined wall 22 of the member 19 and the vertical wall of the recess 18.

The member 19 will be secured in place in the undercut recess 18 in the back 13 of the cup, as by a body of cement 20^a, and the shape of the walls of said recess and the member 19, together with the flange 21, ensures a positive interlock of the parts, as will be clear from the assembly shown in Figs. 1 and 2.

With the member 19 set in the recess 18 in the back of the cup, as described, there will be provided an open-bottomed recess in the member 19, terminating at its top in the wedge-shaped pocket formed by the inclined wall 22 and the vertical wall of the cup, as

heretofore stated. This recess is designed to receive the other securing member 23 of the fixture, which may also be of metal, said member 23 comprising a wall plate having a 5 countersunk aperture 24, and a centering flange 25 surrounding said aperture on the opposite side of the plate. The upper end of the plate 23 is wedge-shaped, as shown, and has preferably a transverse rib 26, or its 10 equivalent, on its face.

The said securing member 23 may be held in place in any suitable manner, but, as here shown, is fastened to the wall or support by means of a toggle bolt, the screw member 27 15 of which is passed through the aperture 24 in the securing member 23, the swing member 28 being then threaded on to the bolt, after which the toggle member may be passed through the aperture 29 in the wall, the swing 20 member brought to binding position, and the screw 27 set up, firmly securing the securing member 23 in place. Preferably the flange 25 will be provided to enter the aperture 30 in the finishing face of the wall, so as to close 25 the same, and center and steady the parts, a washer 31 being preferably placed on the flange 25 and interposed between the wall 11 and the face of the member 23.

With the securing member 23 thus firmly 30 fixed to the wall, the soap dish may be dropped into place, as shown in Fig. 1, with its member 19 wedged down against the rib 26 on the member 23. It will be observed that this 35 ribbed face gives a line engagement between the parts so that there will be a locking and automatic adjustment to compensate for any slight inequalities between the contacting surfaces of the wall 11 and the back of the dish. The tendency is, of course, for the 40 dish to wedge tightly to the wall at all times, and there can be no movement of the dish, except in a vertical direction when it is desired to unseat it. It will be observed that the member 23, as illustrated in Fig. 2, 45 and in dotted lines in Fig. 4, fits snugly the side walls of the member 19, so that no lateral shift or play is permitted.

From the foregoing, it will be seen that a 50 construction is provided which may be readily attached at any point in a wall; by means of which the soap dish may be snugly held to the surface of the support, with the securing parts so interlocked that they cannot be displaced by horizontal pull; and in which all

of the means for securing the dish are 55 concealed, and also protected from drip, so that a sanitary condition is at all times preserved.

Such changes as are within the range of 60 mechanical skill, or as consist of mere adaptations of equivalent mechanical expedients 65 for those here shown may be made and still 70 be within the purview of my invention.

I claim:—

1. The combination of a vitreous lavatory 65 fixture having a recessed wall engaging portion, a metal plate fastened in said recess and having a downwardly projecting projection 70 with an inclined inner face forming with the wall of said recess a wedge-shaped space, and a metal support adapted to enter said recess with its upper end wedged into the space between said projection and the wall of said recess.

2. The combination of a vitreous lavatory 75 fixture having a recessed wall engaging portion, of a metal plate fitted into said recess and having an inclined wall forming with the wall of said recess a wedge-shaped space, a wedge shaped support adapted to enter 80 said recess with its upper and end engaged in the wedge shaped space between said projection and the wall of the recess.

3. The combination of a vitreous lavatory 85 fixture having a recessed wall engaging portion, a metal plate mounted in said recess, a projection at the upper end of said plate having an inclined rear face forming with the wall of the recess a wedge-shaped space, and a support adapted to engage the centrally 90 disposed opening in said plate with its upper end wedged between said inclined wall and the wall of the recess.

4. The combination of a vitreous lavatory 95 fixture having a wall engaging portion provided with an open ended undercut recess; a metal plate of substantially inverted U-shape 100 mounted in said recess and having at one end an inclined face forming, with the wall of the recess, a wedge shaped space; and a support having a substantially wedge-shaped upper end adapted to enter between the legs of said U-shaped plate with its upper end in the wedge-shaped space between said inclined face and the wall of the recess.

In testimony whereof I have hereunto set 105 my hand.

PHILIP MUELLER.
